UNITED STATES PATENT OFFICE.

THOMAS OLSON AND CHRISTIAN HAMMERSBERG, OF LA CROSSE, WISCONSIN.

AUTOMATIC SIGHT-FEED LUBRICATOR.

1,072,978.

Specification of Letters Patent.

Patented Sept. 9, 1913.

Application filed April 15, 1911. Serial No. 621,291.

To all whom it may concern:

Be it known that we, THOMAS OLSON and CHRISTIAN HAMMERSBERG, citizens of the United States, residing at La Crosse, in the 5 county of La Crosse and State of Wisconsin, have invented new and useful Improvements in Automatic Sight-Feed Lubricators, of which the following is a specification.

This invention relates to automatic sight 10 feed lubricators and has particular application to mechanism of the class described adapted particularly for use in connection with locomotives, although we wish it to be understood that we do not limit ourselves 15 in its useful application to the specific purposes herein set forth by way of illustration.

In carrying out our invention it is our purpose to provide a sight feed lubricator 20 by means of which lubricant may be automatically supplied to a pump or the like in predetermined quantities, thereby insuring that lubricant shall not be wasted, and that the pump or other mechanism will be at all 25 times properly oiled.

Still a further object of our invention is to 30 provide improved mechanism of the class described, wherein the lubricator proper may be located at a desired point, such for instance, as within the cab of the locomotive, 35 while the pump is, as is usually the case, situated outside of the cab. By such arrangement the necessity of the engineer going outside of the cabin upon the running board of the locomotive to lubricate the 40 pump is obviated.

With the above recited objects and others 45 of a similar nature in view our invention consists in the construction, combination and arrangement of parts set forth in and falling 50 within the scope of the appended claims.

In the accompanying drawings: Figure 1 is a view partly in elevation and partly in section and showing a locomotive provided with our invention. Fig. 2 is a vertical sectional view taken through the lubricator proper.

Referring now to the accompanying drawings in detail the letter A, is a conventional 55 illustration of a locomotive body having attached thereto in the usual manner, the pump *a*, in one chamber of which moves the piston 1. From this chamber leads the air pipe 2, communicating with the lubricator, the latter being indicated as an entirety by the letter L, said pipe 2 being provided in-

termediate its length, preferably adjacent to the pump, with a valve connection 3 in which is located the valve 3^a which opens upward under pressure of air forced through the pipe 2 by the piston 1 in the pump *a*. The 60 lubricator L is divided into two chambers *c* and *d*, through the medium of the diaphragm *x* and within the lower chamber *c* is located a valve 4, seating at 4^c on the port leading from the pipe 2 to the lubricator. 65 The stem of the valve 4 contacts with the underside of the lever 4^a which in turn is pivoted to the stud or lug 4^b secured to the base of the lubricator body. Carried intermediate the ends of the lever is the valve 70 5 controlling the port *c*, leading to the return pipe 6, the latter being connected to the pump, and having located adjacent to said pump, the valve connection 7 in which is located the valve 7^a. This valve 7^a is 75 similar in construction to the valve 3^a, and when the valve 3^a is closed on the down stroke of the piston 1, the valve 5 controlling the port *c* in the lubricator also closes and the valve 7^a is then forced upward or 80 open by the pressure in the return pipe 6 between said valve and the valve 5. It will thus be seen that on the upward stroke of the piston, the air in the cylinder is forced through the pipe 2 opening the valve 85 3^a and thus permitting the air to pass to the lubricator. On the downward stroke of the piston, the valve 3^a closes, as does the valve 5 and the valve 7^a simultaneously opens permitting the oil and air which is 90 passed into the return pipe 6 to flow to the pump.

The lubricator L is preferably constructed as follows: The numeral 9 designates the base plate adapted to be threaded onto the 95 end of the body of the lubricator, said base plate carrying the ports and channels controlled by the valves 4 and 5. The numeral 10 designates the feed valve of the device, while the character 10^a is the bonnet 100 surrounded by the packing nut 10^b, the valve stem 10^c passing through said nut and bonnet and being operated by the hand wheel 10^d to control the passage of the lubricant through the port or channel 10^e in the diaphragm between the chambers *c* and *d*. In filling the chamber the lubricant is admitted through the inlet 11 controlled by the screw plug 12, while the numeral 13 indicates an 105 equalizing pipe arranged between the cham- 110

bers *c* and *d* for equalizing the pressures between such chambers. If preferred the lever 4^a, with which are connected the stems of the valves 4 and 5, may be tensioned through the medium of the spring 16 carried by the stud 16^a which extends upward from the base of the lubricating chamber. We may also employ the cut-off valve 15 located upon the pipe 2, should the same be deemed necessary.

From the above description taken in connection with the accompanying drawings, the construction and operation of the improved sight feed lubricator will be readily apparent to those skilled in the art.

Assuming the piston within the air chamber to be in the position shown in Fig. 1 of the drawings, that is upon the upward stroke, the air from the piston chamber is forced into the pipe 2, to the valve 3^a, said valve being raised to permit said air to pass onward through the pipe to the port controlled by the valve 4. Said valve being raised by the air pressure also operates the valve 5 through the lever connection and the oil or other lubricant which has been delivered into the lower chamber flows into the pipe 6, and as the latter is preferably a continuous slope from the lubricator to the pump, the oil will pass downward into the pump and to the proper parts to be lubricated.

The downward stroke of the piston relieves the air pressure on the valves 3^a, 4 and 5, which valves close, thus shutting off the air pressure to the lubricator and such downward stroke of the piston also permits the valve 7^a to be opened by the pressure of oil and air in the return pipe 6 between the valve 5 and the valve 7^a, so that the lubricant may flow through the valve 7^a to the pump. A certain proportion of the air remains in the chamber in the lubricator at the highest pressure carried by the engine, and the only waste of air is that which is taken into the return pipe 6 on each stroke of the pump.

While we have herein shown and described one particular embodiment of our invention, we wish it to be understood that we do not confine ourselves to all the precise details set forth, as modification and variation may be made without departing from the spirit of the invention or exceeding the scope of the appended claims.

What we claim is:—

1. In a lubricator, the combination with a source of fluctuating pressure, of a lubricant container, a connection between said source of pressure and lubricant container whereby the lubricant may be placed under pressure, a conduit for the lubricant leading from the container to said source, and means normally holding said connection and conduit closed and operable from the pressure of said source to open said connection and conduit simultaneously.

2. The combination with a pump having an air chamber therein, of a lubricator comprising a body portion divided into a plurality of chambers, an air conduit leading from the pump to the lowermost of said chambers, a lubricant conduit leading from said chamber back to the pump, a valve for each of said conduits, and a connection between said valves whereby the latter are simultaneously operated by the pressure of air within the air conduit.

3. The combination with a pump having an air chamber formed therein, a piston moving within said chamber, of a lubricator comprising a body portion divided into an upper and a lower chamber communicating one with the other, a valve for controlling the communication between the chambers, an air conduit leading from the air cylinder of the pump to the lower chamber of the lubricator, a check valve controlling the passage of air from said air cylinder to the air conduit, and a second valve within the lower chamber of the lubricator and controlling the passage of air to said chamber, a conduit for the lubricant leading from the lower chamber of the lubricator to the pump, a check valve within said conduit, a second valve controlling a port within the lower chamber of the lubricator, which port communicates with the lubricant conduit, and a connection between the valves within said lower chamber whereby said valves are simultaneously operated to permit the automatic delivery of lubricant to the pump.

In testimony whereof we affix our signatures in presence of two witnesses.

THOMAS OLSON.
CHRISTIAN HAMMERSBERG.
